UNITED STATES PATENT OFFICE.

IRVING F. WEBB, OF ELIZABETH, NEW JERSEY, ASSIGNOR TO THE SINGER MANUFACTURING COMPANY, A CORPORATION OF NEW JERSEY.

FILLED-SACK-SEWING MACHINE.

1,401,296.

Specification of Letters Patent. Patented Dec. 27, 1921.

Application filed January 24, 1918. Serial No. 213,509.

To all whom it may concern:

Be it known that I, IRVING F. WEBB, a citizen of the United States, residing at Elizabeth, in the county of Union and State 5 of New Jersey, have invented certain new and useful Improvements in Filled-Sack-Sewing Machines, of which the following is a specification, reference being had therein to the accompanying drawings.

10 This invention relates to improvements in filled sack sewing apparatus including a sack conveyer and a sewing mechanism, and has for an object to provide actuating means for the sewing mechanism controlled independently of the actuating means for the sack-conveyer.

The invention has for a further object to provide a separate control for each of said actuating mechanisms.

20 Another object of this invention is to provide actuating mechanism for the sack-conveyer permitting the required adjustments of the conveyer.

Other objects of this invention will be 25 apparent from the following description and claims.

In its preferred embodiment, the present improvement comprises a filled sack sewing apparatus having a suitable frame-work 30 supporting a vertically adjustable sack-conveyer and an overhanging sewing head. The actuating mechanism for the sack-conveyer consists of an electric motor, supported by a bracket secured to the conveyer-frame and 35 having driving connections with the loose pulley of a power transmitter. This power transmitter is controlled by a treadle in a manner permitting vertical adjustment of the transmitter without affecting the position 40 of the treadle. The sewing machine is driven from a motor secured to the framework of the apparatus through the intermediary of a power transmitter also secured to the frame-work and adapted to be controlled by a treadle independent of the treadle controlling the operation of the conveyer.

The invention will be understood by reference to the accompanying drawings, in which Figure 1 is a view in elevation of the 50 rear side of the apparatus. Fig. 2 is a plan view of the apparatus with portions thereof broken away to better illustrate the mechanisms more pertinent to the present invention. Fig. 3 is a left hand elevation of the 55 machine, or more particularly an end eleva-

tion as viewed from the right in Fig. 1. Fig. 4 is a sectional view of the conveyer-actuating power-transmitter. Fig. 5 is a sectional view of the right-hand conveyer-frame supporting-bracket as viewed from 60 Fig. 1. Fig. 6 is a sectional view of the left-hand conveyer-frame supporting-bracket as viewed from Fig. 1. Fig. 7 is a sectional view on the line A—A of Fig. 6. Fig. 8 is a detail view of the conveyer-actuating-motor 65 supporting-bracket.

Referring to the drawings, the filled sack sewing apparatus comprises a base 1 from which rise the upwardly projecting standards 2 and 3, supporting the table 4. Secured to the table 4 is a bracket 5 carrying the overhanging sewing machine 6 of well known construction. The driving pulley 7 of the sewing machine is driven by a belt 8 passing over the adjustable idler-pulleys 75 9 and 10 mounted on the supporting post 11 secured to a base 12 suitably positioned upon the table 4. Beyond the idler pulleys, the belt 8 passes through suitable apertures in the table 4 and around the driving pulley 14 80 of a power transmitter 15 of a well-known type and supported by a bracket 16, secured to the under side of the table 4. The loose pulley 17 of the power transmitter is adapted, to be clutched to or unclutched from the 85 driving pulley by means of the usual starting- and brake-lever 18, connected by means of the relatively adjustable rods 19 and 20 with a lateral arm 21 secured to a rock-shaft 22. The rock-shaft 22 is supported in bearings 23 and 24, secured to the base 1 of the apparatus and is acted upon by a spring 25 to normally hold in a substantially vertical position the treadle 26 secured upon the rock-shaft 22 by means of the collar 27. The 90 loose pulley 17 of the power transmitter 15 is constantly driven by means of a belt 28 from the electric motor 29 supported by the base 1.

Positioned below the sewing machine 6 100 is the conveyer comprising an endless carrier-belt 30 passing around the driving pulley 31 and guiding pulley 32. These pulleys are journaled in bearings provided in a conveyer-frame 33 supported by brackets 34 105 and 35. The bracket 34 is provided with upwardly projecting lugs, as 36, forming bearings for a pivot-pin 37, held against end-wise movement by the collars 38 and entering suitable apertures in the opposite sides 110

of the conveyer-frame 33 for a purpose hereinafter described. The bracket 35 is formed with elongated slots, as 39, entered by pins, as 40, screw-threaded into the conveyer-frame 33 resting upon the bracket. Each of the brackets is secured by bolts, as 41, to nuts, as 42, to permit sliding movement upon the standards 2 and 3. Threaded into the nuts 42 are vertical screw-rods, as 43, supported in bearings, as 44, and carrying bevel-gears, as 45, in mesh with similar gears, as 46, upon horizontal shafts, as 47, journaled in bearings, as 48, on the under side of the table 4 and carrying crank-handles, as 49. By simultaneously manipulating the handles 49, it is evident that any desired vertical adjustment of the conveyer may be obtained. When one of the crank-handles is manipulated slightly faster than the other, the conveyer-frame 33 swings on the pivot-pin 37, which is permitted by the provision of the slots 39 in the bracket 35.

The driving pulley 31 for the carrier-belt is mounted on the shaft 50, coupled by means of the ribbed-washer 51 with the power transmitting shaft 52 rotatively supported upon a bracket 53 secured by bolts, as 54, to the conveyer-frame 33. The power transmitter, as usual, includes a continuously driven loose pulley 55 and a driving pulley 56 adapted to be forced into driving engagement with the pulley 55 by means of a starting- and brake-lever 57. The pulley 56 is keyed to the driving member 58 of a planetary gearing and carrying a pair of double spur-gears 59 and 60 mounted to rotate upon their own axes. The gears 59 mesh with the stationary spur-gear 61 carried by the shaft 62, upon which the loose pulley 55 is mounted to rotate and which shaft is rigidly bolted to the bracket-extension 63 of the bracket 53. The spur-gears 60 have a smaller number of teeth than the spur-gears 59 and mesh with the spur-gear 64 keyed to the shaft 52. By means of this construction, the desired driving ratio of the pulley 56 relatively to the shaft 52 may be obtained.

The loose pulley 55 is constantly rotated by a belt 65 driven by an electric motor 66 supported by a bracket 67 secured by bolts, as 68, to the conveyer-frame 33. Consequently the actuating means for the carrier belt 30 maintains a definite relative position with regard to the conveyer-frame 33 in spite of any adjustments of the conveyer-frame.

To the starting- and brake-lever 57 is secured one end of a spring 69 of which the other end is secured to a post 70 projecting from the bracket-extension 63, this spring acting to hold the lever 57 in contact with the vertical rod 71 secured by rods 72 to the vertical fulcrum-rod 73, supported at its upper end in a bearing 74 secured to the un-

der side of the table 4, and at its lower end in a bearing 75 on the base 1. The rod 71 is connected by means of a longitudinally adjustable link 75' with a crank-arm 76 secured to a treadle actuated rock-shaft 77 mounted in bearings 78 and 79 on the base 1. A foot-plate or treadle 80 is secured to the rock-shaft and is normally held in raised position by a spring 81, the action of the spring being limited by a stop-pin 82 secured to the shaft and adapted to bear upon the base 1. By pressing downward upon the treadle 80, the consequent actuation of the rock-shaft causes the rod 71 to swing about its fulcrum and thereby act upon the lever 57 to force the driving pulley 56 into frictional contact with the constantly rotated pulley 55. The treadle connections described are entirely independent of the mechanism for actuating the sewing machine and permit vertical adjustment of the conveyer-frame 33 and its actuating mechanism.

Having thus set forth the nature of the invention, what I claim herein is—

1. In a filled-sack sewing apparatus, the combination with a supporting frame-work, sewing mechanism supported by said frame-work, a motor carried by the latter and a treadle for controlling power transmission between said sewing mechanism and motor, of a sack conveyer-frame, means permitting vertical adjustments of said sack conveying frame, sack-conveying means supported by said frame, and means for actuating said sack-conveyer means including a motor and a power transmitting clutch carried by said frame.

2. In a filled sack sewing apparatus, the combination with a supporting frame-work, sewing mechanism supported by said frame-work, and actuating means for said sewing mechanism, of a sack-conveyer frame, sack-conveying means supported by said conveyer-frame, means including a motor, a power-transmitter and a belt connection also supported by said conveyer-frame for actuating said sack-conveying means, and a treadle for controlling the sack-conveying actuating means.

3. In a filled-sack sewing apparatus, the combination with a supporting frame-work, sewing mechanism supported by said frame-work, actuating means for said sewing mechanism, and a treadle for controlling said actuating means, of a sack-conveyer frame, sack-conveying means supported by said conveyer frame, means including a motor and belt connection also supported by said conveyer-frame for actuating said sack-conveying means, and a treadle for controlling the sack-conveying actuating means.

4. In a filled sack sewing apparatus, the combination with a supporting frame work, a sewing mechanism and actuating means therefor, of a sack-conveyer frame, sack-

- conveying means supported by said conveyer-frame, and means including a motor supported by said conveyer-frame for actuating said sack-conveying means, said sack-
5 conveying means and its actuating mechanism being together adjustable relatively to said sewing mechanism.
5. In a filled-sack sewing apparatus, the combination with a supporting frame-work, 10 sewing mechanism supported by said frame-work, and actuating means for said sewing mechanism, of a sack-conveyer frame, sack-conveying means supported by said conveyer-frame, a power transmitting clutch mechanism supported by said conveyer-frame controlled to effect and arrest the 15 transmission of power to said conveying means, and means for actuating said power transmitter, said conveyer and its actuating mechanism comprising a unit of construction carried by said supporting frame and together adjustable relatively to said sewing mechanism.
6. In a filled-sack sewing apparatus, the combination with a supporting frame-work, 20 sewing mechanism supported by said frame-work, and actuating means for said sewing mechanism, of a sack-conveyer frame, means permitting vertical adjustments of said sack-
30 conveying frame, sack-conveying means supported by said conveyer-frame, a power transmitter supported by said conveyer-frame, for actuating said sack-conveying means, and means also supported by said conveyer-frame for actuating said power transmitter.
7. In a filled-sack sewing apparatus, the combination with a supporting frame-work, 35 sewing mechanism supported by said frame-work, means for transmitting power to said sewing mechanism, and an electric-motor supported by said frame-work for supplying power to said means, of a sack-conveyer frame, means permitting vertical adjustments of said sack-conveying frame sack-
40 conveying means supported by said conveyer-frame, a power-transmitter supported by said conveyer-frame for actuating said
- sack-conveying means, and an electric-motor also supported by said conveyer-frame for transmitting power to said power-transmitter. 50
8. In a filled sack sewing apparatus, the combination with a supporting frame-work, 55 sewing mechanism supported by said frame-work, and actuating means for said sewing mechanism, of a sack-conveyer frame, a supporting bracket, a pivotal support for said conveyer-frame on said bracket, a second supporting bracket for said conveyer-frame, 60 means for vertically adjusting said conveyer-frame, and means afforded by the support of said conveyer-frame on said second bracket for permitting swinging movement of said conveyer-frame on its pivotal support during said vertical adjustment. 65
9. In a filled-sack sewing apparatus, the combination with a supporting frame-work, 70 sewing mechanism supported by said frame-work, and actuating means for said sewing mechanism, of a sack-conveyer frame, means permitting vertical adjustments of said sack-conveying frame, sack-conveying means supported by said conveyer-frame, and a power transmitter for actuating said sack-conveying means, said power transmitter including 75 a planetary-gearing for obtaining the necessary driving ratio between the power transmitter and the conveying means.
10. In a filled-sack sewing apparatus, the combination with a supporting frame-work, 80 sewing mechanism supported by said frame-work, and actuating means for said sewing mechanism, of a sack-conveyer frame, sack-conveying means supported by said conveyer-frame, means also supported by said conveyer-frame for actuating said sack-conveying means, a treadle for controlling the sack-conveying actuating means, and means for vertically adjusting said sack-conveying 85 means and its actuating mechanism without affecting the treadle-control of said actuating mechanism. 90

In testimony whereof, I have signed my name to this specification.

IRVING F. WEBB.
